UNITED STATES PATENT OFFICE.

WILLIAM E. WHITE, OF MILWAUKEE, WISCONSIN.

KNIT CAP AND METHOD OF MAKING SAME.

Application filed January 14, 1924. Serial No. 686,116.

To all whom it may concern:

Be it known that I, WILLIAM E. WHITE, a citizen of the United States, and resident of Milwaukee, in the county of Milwaukee, and State of Wisconsin, have invented certain new and useful Improvements in Knit Caps and Methods of Making Same; and I do hereby declare that the following is a full, clear, and exact description thereof.

This invention relates to knit caps and to a method of making such caps.

It is well known that it is more expensive to produce circularly knit caps than it would be to produce caps formed of flat knit material.

Objects of this invention are to provide a cap formed of blanks made of flat knit material, to provide a cap having all of the seamed edges hidden from view, and to provide a cap which although formed of flat knit material is nevertheless fashioned to accurately and comfortably fit the head.

Further objects are to provide a method of forming fashioned caps from flat knit material in a simple and rapid manner, and to provide a method which will materially reduce the cost of making such caps.

An embodiment of the invention is shown in the accompanying drawing, in which:

Figure 1 is a view of the main piece or blank.

Figure 2 is a view of the auxiliary piece.

Figure 3 is a view of the completed cap showing the ear lap strip turned down, parts being broken away to show the interior construction.

Figure 4 is a view of the completed cap with the ear lap strip turned up.

Figure 5 is a fragmentary sectional view on an enlarged scale, such view corresponding to a section on the line 5-5 of Figure 3.

The cap is formed throughout of flat knit material and comprises a main body portion 1 of rectangular contour formed of flat knit material. This body portion is formed with rectangular side notches 2 and with an upper substantially centrally located notch 3. The side notches 2 it is to be noted define an ear lap strip 4 integrally joined to the main portion of the rectangular member. In forming the cap the sides 5 of the rectangular notch are stitched to the bottom portion 6 thereof, as shown in Figure 3,—it being understood that the portion 6 may be slightly gathered if desired. Thereafter, the edges 7 of the top are stitched together

to form a central vertical seam, as shown in Figure 3. The edges 8-8 and 9-9 of the notches 2 are respectively stitched together. One of the resulting side seams is shown in Figure 3, the other seam, of course, being similar and symmetrically located.

An auxiliary piece of material 10 (see Figure 2) is cut from flat knit material and comprises a rectangular lower portion and a triangular upper portion, as shown in Figure 2. The vertical edges 11 of this auxiliary piece of material are secured within the side seams preferably at the time said side seams are formed, that is to say, one of the side seams includes the edges 8-8 of the member 1 and edge 11 of the member 10 and the other side seam includes 9-9 of the member 1 and the opposite edge 11 of the member 10. The lower edge 12 of the member 10 is secured throughout its extent to the lower front edge of the cap, as shown in Figure 2, such lower front edge being formed by the edges 13 of the blank 1, shown in Figure 1. At the same time that the bottom edge 12 of the member 10 is secured, the ends of the ear lap strip 4 are turned inwardly, as shown in Figure 3, and the edges 14 thereof are secured, together with the edge 12 of the member 10, to the edges 13 of the blank 1.

In Figure 5 an enlarged sectional detail on the line 5-5 of Figure 3 is shown and it illustrates edge 11 as positioned adjacent the edges 9 and the member 10.

The apex of the member 10 is secured to the body portion of the cap in any suitable manner as by means of stitching through an ornamental button 15 (see Figure 4). This maintains the auxiliary piece 10 in its elevated position and completely hides the central vertical seam and the side vertical seam so that no seams are exposed to view in the completed cap.

It is to be noted that the ear lap 4 is provided with button holes 16 adjacent its opposed edges and that when such ear lap strip is turned up in Figure 4, these button holes may cooperate with buttons 17 stitched through the member 10 to the body portion 100 of the cap. If desired, an auxiliary strip of material, as indicated in dotted lines at 18 in Figure 4, may be employed and may be provided with any suitable securing means to retain it in a hidden position. One end of this strip 18 is stitched to a portion of the ear lap strip 4 and the other end

is provided with a button hole adapted to engage a button such as indicated at 19 in Figure 4 upon the other end of the ear lap strip, so that when such ear lap strip 5 is folded downwardly this strip 18 may be employed to hold adjacent ends of the member 4 closely about the neck of the wearer.

It will be seen that a knit cap has been provided which is formed of flat knit material throughout and that all the seams employed in the fashioning of the cap are completely hidden in the finished article.

It will further be seen that a method of making knit caps from flat knit material has 15 been provided and that this method may be very quickly and easily followed with a minimum of expense and effort.

Although the invention has been described in considerable detail, it is to be understood 20 that the invention may be variously embodied and is, therefore, to be limited only as claimed.

I claim:

1. A knit cap formed of pieces of flat 25 knit material comprising a body portion formed of a rectangular piece of material having side notches and having a front vertical central seam joining portions of the upper edge of said piece, and having side 30 vertical seams joining adjacent edges of said notches, and a flat piece of material having a triangular upper portion and a rectangular lower portion, said rectangular lower portion having its side edges secured in said 35 side vertical seams, whereby said vertical seams are hidden.

2. A knit cap formed of pieces of flat knit material comprising a body portion formed of a rectangular piece of material having 40 side notches and having a front vertical central seam joining portions of the upper edge of said blank, and having side vertical seams joining adjacent edges of said notches, a flat piece of material having a triangular 45 upper portion and a rectangular lower portion, said rectangular lower portion having its side edges secured in said side vertical seams, whereby said vertical seams are hidden, and an ear lap integrally joined to

the lower portion of said first mentioned 50 rectangular piece and stitched to the side edges of such first mentioned rectangular piece.

3. The method of making a knit cap from flat knit material which method comprises 55 notching the sides of a rectangular piece of knit material, seaming the adjacent edges of said notches to form vertical side seams, seaming opposite portions of the top edge of said rectangular piece to form a central 60 vertical seam, and securing the side edges of an auxiliary piece of material within the side seams and securing the lower edge of said auxiliary piece of material to portions of the side edges of said rectangular piece of 65 material.

4. The method of making a knit cap from flat knit material which method comprises notching the sides of a rectangular piece of knit material, to form a transverse, 70 rectangular lower ear lap strip, seaming the adjacent edges of said notches to form vertical side seams, seaming opposite portions of the top edge of said rectangular piece to form a central vertical seam, and securing the side edges of an auxiliary piece of material within the side seams, securing the lower edge of said auxiliary piece of material to portions of the side edges of said 75 rectangular piece of material, and securing 80 portions of said ear lap strip to the side portions of said first piece of material.

5. A knit cap formed of pieces of flat knit material comprising a body portion formed of a rectangular piece of material having 85 side notches and having a front vertical seam joining portions of the upper edge of said rectangular piece, and having side vertical seams joining adjacent edges of said notches, and an auxiliary piece of material 90 having its side edges secured in said side seams whereby all of said seams are hidden by said auxiliary piece of material.

In testimony that I claim the foregoing I have hereunto set my hand at Milwaukee, 95 in the county of Milwaukee and State of Wisconsin.

WILLIAM E. WHITE.
